(No Model.)

W. T. SMITH.
DRIVING GEAR FOR VELOCIPEDES.

No. 596,289.

Patented Dec. 28, 1897.

UNITED STATES PATENT OFFICE.

WILLIAM THOMAS SMITH, OF BOLTON, ENGLAND.

DRIVING-GEAR FOR VELOCIPEDES.

SPECIFICATION forming part of Letters Patent No. 596,289, dated December 28, 1897.

Application filed August 31, 1896. Serial No. 604,372. (No model.)

To all whom it may concern:

Be it known that I, WILLIAM THOMAS SMITH, a subject of the Queen of Great Britain, residing at Church Street, Bolton, Lancaster county, England, have invented certain new and Improved Driving-Gear for Velocipedes, of which the following description is a specification.

In connection with the driving-gear of velocipedes which are propelled by the rider operating rotary cranks it is well known that the power exercised by said rider over said cranks, as well as the speed of these latter, is least and slowest in that part of each of their revolutions wherein these said cranks are most nearly approaching their highest and lowest positions. To counteract this and distribute the power of the rider over the vehicle more evenly throughout the entirety of each revolution of the crank without entailing the use of mechanism which will greatly add to the cost of production of the velocipede or which will engender other disadvantages is the object of this invention, and this object I attain by the employment of the mechanism illustrated by the accompanying sheets of drawings, in which—

Figure 1 is a part sectional elevation of such a portion of a velocipede with my improved driving-gear applied thereto as is necessary to show how the latter may be put into use. Figs. 2 and 3 are similar views to Fig. 1, but show in each case the employment of only one guide-pulley, the same being mounted to guide the chain in its upper and lower paths, respectively.

Similar letters of reference indicate similar parts throughout the several views.

B indicates portions of the velocipede's framework upon which the crank-spindle *a* and the spindle *b* of the velocipede's driving-wheel *f* are mounted, while *c*' are the cranks fixed to said spindle *a* and carrying the pedals *d*'. On the spindle *a* I fix the well-known elliptical driving-wheel *e*, its larger diameter being at or about right angles to the radial arms or cranks *c*'. Thus when these cranks *c*' are in position for the rider to have the greatest power over them this power or force will at this time be transmitted by the chain *g* to the driving-wheel *f* through the greater diameter of the elliptical wheel *e* in a manner

well understood. However, when this elliptical driving-wheel *e* has heretofore been employed in one form of machine it has been 55 found that on account of the varying tension of the chain *g* this latter frequently left or was thrown off the wheel *h*, attached to the driving-wheel *f*, thus adding greatly to the risk of accident to the rider. To obviate this 60 defect and cause the tension of the chain *g* to be as unvarying as it is when the ordinary circular driving-wheel is employed, I secure an ordinary sprocket-wheel *h*' on the hub of the rear wheel, while guide-pulleys *p* *p*', 65 mounted to revolve on fixed bearings *q* *q*', are arranged in such positions relatively with the wheel *e* as to keep the chain *g* at its proper tension, this position being clearly defined as the center of the arc 3 4, (shown in broken lines, Fig. 1,) which bisects the horizontal planes in which the chain *g* travels and the vertical plane through the spindle *a*. Thus the slight variations in the tension of the chain *g* are represented by the distance that 70 said arc 3 4 passes out of the vertical line 1 2. In other words, each of the wheels *p* or *p*' is so situated in its fixed location that although it deflects the chain but slightly, if at all, when the longer radii of the elliptical wheel 75 are at a right angle to the path of movement of the wheel it materially deflects said chain when the shorter radii of the elliptical wheel are at a right angle to said path of movement. This will be evident by referring to 80 Fig. 1, from which figure it will be clear that if the guide-wheels were omitted the chain would be very slack or loose when the elliptical wheel is in the position indicated by 85 full lines in said figure. Again, I find that 90 one guide-wheel *p*, as shown by Fig. 2, or one, *p*', as shown by Fig. 3, is quite sufficient to maintain the chain *g* in its proper positions on the wheels *e* *h*', and either or any of these devices may be employed when the wheel *e* 95 has a circumference greater or less than twice that of the wheel *h*'.

Having thus described the nature and object of my invention, what I consider new, and therefore claim, is—

1. In a velocipede, the combination of an elliptical driving chain-wheel, a concentric driven chain-wheel, a chain connecting them, and a concentric guide-wheel mounted to re-

volve on fixed bearings, the outer portion of the periphery of the guide-wheel being situated outside of a line drawn from the periphery of the concentric driven wheel to the shorter radius of the elliptical wheel, whereby the path of movement of the chain is deflected more or less according to whether the shorter or the longer radius respectively of the elliptical wheel is at a substantial right angle to said path of movement.

2. In a velocipede, the combination of an elliptical driving chain-wheel, a concentric driven chain-wheel, a chain connecting them, and a pair of concentric guide-wheels, one for each stretch of the chain and mounted to re-

volve on fixed bearings, each of said guide-wheels having the outer portion of its periphery situated outside of a line drawn from the periphery of the concentric driven wheel to the shorter radius of the elliptical wheel, whereby the path of movement of the chain is deflected more or less according to whether the shorter or the longer radii respectively of the elliptical wheel are at a substantial right angle to said path of movement.

WILLIAM THOMAS SMITH.
